DETACHABLE CROTCH GIRDLE

Sam Davis, New York, N. Y.

Application May 7, 1935, Serial No. 20,249

1 Claim. (Cl. 2—43)

This invention relates to a detachable crotch girdle and has for an object to provide an improved girdle having a readily attachable and detachable crotch.

5 Girdles are generally made of elastic stretchable material and as such are rather difficult to wash properly. Due to this fact girdles in use are apt to become more or less insanitary especially in the crotch portion. Attempts have been
 10 made to meet this problem by omitting the crotch all together, but when this is done it is difficult to keep the girdle properly in position and further the girdle is not very satisfactory in use.

In order to overcome this objection, this invention provides a detachable crotch portion in the girdle which crotch portion may be quickly and easily detached from the girdle and a fresh clean crotch piece may be quickly and easily attached as a substitute therefor. The soiled crotch
 20 piece may then meantime be laundered and made sanitary so as to replace the other crotch piece that is meantime to become soiled. Obviously, any number of separate crotch pieces may be provided for an individual girdle of this invention
 25 so that it is not essential to launder the individual crotch piece so often.

As a further feature of this invention the attaching means for the crotch piece and the girdle is so cooperative that the crotch piece remains firmly in position and does not bear uncomfortably against the body of the wearer in any position. As an additional feature, the crotch piece has a selvage edge similar to the selvage edge on the girdle and forming a continuation thereof when in attached position.

An additional feature and advantage of this invention is that the crotch piece may be temporarily detached while wearing this girdle in order to perform the natural functions. Yet a further feature of this invention is that the separable crotch piece is substantially rectangular in outline whereby it may be made with no waste of material as would be necessary were it of irregular outline. The crotch piece itself will be made of a material that may be easily laundered, such as silk, glove silk, rayon, cotton and like material, while the remainder of the girdle may continue to be made of the usual elastic filled stretchable material that need be laundered at less frequent intervals.

With the foregoing and other objects in view, as will hereinafter become apparent, this invention comprises the constructions, combinations and arrangements of parts, hereinafter set forth,

disclosed and shown on the accompanying drawing. In this drawing,

Figure 1 is a front plan view of the girdle in operative position,

Figure 2 is a sectional view through the center 5 of the girdle looking toward one side, the detachable crotch piece having been removed,

Figure 3 is a plan view of the detachable crotch piece, and

Figure 4 is an elevational view showing the 10 crotch piece being applied to the girdle.

There is shown at 10 a girdle made of the usual heavy knit elastic material having an upper selvage edge 11 about the waist line and the lower selvage edge 12 extending about the lower edges 15 of the leg portions 13. Depending from this lower selvage edge 12 is a pair of garters 14 on each leg portion 13.

The detachable crotch piece 15 forming an important feature of this invention, is preferably 20 made of an easily launderable material such as silk, glove silk, rayon, cotton, or other like material. This crotch 15, as is apparent from Figure 3, is substantially rectangular in outline. Two edges 16 of the crotch piece 15 will preferably be 25 selvage edges similar to the selvage edges 11 and 12 and in assembled position the selvage edges 16 form continuations of the selvage edges 12 on the leg portions 13. The other two edges 17 of the crotch piece 15 are provided with reinforcing tape portions 18 securely stitched to the crotch piece 15 as at 19 and 20. The tape portions 18 provide a support for the fastening means secured to the inner side thereof and projecting therethrough, this fastening means comprising 35 snap members. Preferably the male portion of the snap member such as 21 is extended through the tape 18 and then secured thereto by stitching 22 before the tape 18 is stitched in position as at 19 and 20. On the girdle 10 the crotch piece 40 securing means includes a similar tape piece 23 having secured to the underside thereof a plurality of female portions 24 of the snap fasteners by means of stitching 25. With the suitable appropriately spaced number of female portions 45 24 of snap fasteners thereon, the tape 23 is secured to the top of a relatively non-stretchable tape material 26.

This non-stretchable tape piece 26 is secured along the crotch edge by means of a selvage edge 50 27 with a heavy knitted elastic portion of the girdle 10. As a result of such construction the crotch piece 15 makes the leg portions 13 form fitting about the leg and the crotch thus making the entire girdle 10 neat and form fitting. 55

When in position no metal portion of either the male or female sections of the snap fasteners can contact either with the body of the user to irritate the skin, or with the outer clothing of the user to wear or tear the same. The protch piece 15 will naturally be soiled more easily and more quickly than the remainder of the girdle and when this has happened it is quickly and easily removed for laundry by separating the snap fasteners and a new or freshly laundered crotch piece 15 is placed in position. This can be done either while the girdle is on the body of the user, or while the girdle has been removed from the body of the user. Furthermore, the crotch piece 15 may be easily temporarily detached to permit the natural functions and then may be replaced in position thereafter.

When in position the crotch piece 15 makes the girdle just as neat and as form fitting as though the crotch piece 15 were an integral and non-separable part of the girdle so that the advantages of a girdle having a non-separable crotch piece are preserved while adding thereto the advantages of a girdle having a separable crotch piece. By making the crotch piece substantially rectangular in outline there is a considerable economy in manufacture and elimination of any waste pieces, as the maximum number of crotch pieces can be cut from a given bolt of material when the pieces are of this regular rectangular outline.

It is thus possible to inexpensively provide a number of separable crotch pieces to accompany each girdle as it is sold to the user so that a freshly laundered crotch piece may be used each time that the girdle is placed on the body of the user if so desired. The girdle itself being of a heavy knitted elastic material can likewise be

laundred whenever needed, but due to its construction it is naturally a more difficult problem to laundred the girdle itself as with this invention the excessive wear and tear of too frequent laundering of the girdle itself is avoided, thereby lengthening the life of the girdle which is comparatively expensive compared to the crotch piece itself which may be laundered with every use.

The novel features and the operation of this device will be apparent from the foregoing description. While the device has been shown and the structure described in detail, it is obvious that this invention is not to be considered limited to the exact form disclosed and that changes may be made therein within the scope of what is claimed without departing from the spirit of the invention.

Having thus set forth and disclosed the nature of this invention, what is claimed is:

A form fitting girdle of elastic material having a cut-out crotch at the front and rear and a detachable crotch piece of inelastic material adapted to fit such cut-out crotch, and cooperative fastening means on said girdle and on said crotch piece for attaching said crotch piece to said girdle, said fastening means on said girdle including an inelastic tape along the sides of the cut-out crotch, said girdle being provided with selvage edges, and two opposite edges of the detachable crotch piece being provided with selvage edges adapted to form a continuation of the selvage edges of the leg portion when in position, the inelastic fastening tape of said girdle holding the elastic girdle in form fitting position enabling the girdle to be used without the crotch piece.

SAM DAVIS.
